No. 36,548.

Patented September 8, 1903.

UNITED STATES PATENT OFFICE.

WILLIAM L. DENIO, OF ROCHESTER, NEW YORK, ASSIGNOR OF ONE-HALF
TO HOBART F. ATKINSON, OF ROCHESTER, NEW YORK.

DESIGN FOR A FIRE-ALARM BOX.

SPECIFICATION forming part of Design No. 36,548, dated September 8, 1903.

Application filed May 12, 1903. Serial No. 156,845. Term of patent 14 years.

To all whom it may concern:

Be it known that I, WILLIAM L. DENIO, a citizen of the United States, residing at Rochester, in the county of Monroe, in the State of New York, have invented a new, original, and ornamental Design for Fire-Alarm Boxes, of which the following is a specification, reference being had to the accompanying drawings.

10 In the accompanying drawings, Figure 1 is

a front view of a fire-alarm box embodying my new design, and Fig. 2 is a side elevation of the same.

I claim—

The ornamental design for a fire-alarm box 15 as shown.

WILLIAM L. DENIO.
